PORTABLE, VERTICALLY ADJUSTABLE, AND
COLLAPSIBLE STAND

Harry E. Eller, Chicago, Ill.

Application December 31, 1943, Serial No. 516,571

7 Claims.

(Cl. 169—24)

The invention relates to new and useful improvements in stands and has particular reference to portable, vertically adjustable, and collapsible stands.

The invention is primarily concerned with portable and collapsible stands which are adapted to support screens for the reception thereon of light-projected motion and still pictures and for supporting maps and pictorial reproductions of various kind and nature.

The present invention has among its objects to provide novel features of construction in a portable screen affording adjustment of the screen both as to height and area for the proper framing of the projected picture at various desirable elevations.

It is a further object of the invention to provide certain features of construction and arrangement of parts tending to enhance the efficiency and utility of a device of the character specified.

With these and other objects in view which will become apparent from a perusal of the invention the latter comprises the means described in the following specification, particularly pointed out in the claims forming a part thereof, and illustrated in the accompanying drawings in which:

Fig. 1 is a front view of a stand constructed in accordance with the invention;

Fig. 2 is a cross section taken on the line 2—2 of Fig. 1;

Fig. 3 is a vertical section taken on line 3—3 of Fig. 2;

Fig. 4 is an end view of the stand;

Fig. 5 is a fragmentary end view of the stand in collapsed position;

Fig. 6 is an enlarged view of the adjustable combined carrying handle, screen roller casing support, and frictional locking means;

Fig. 7 is a cross section taken on line 7—7 of Fig. 6 showing the extension rod lock;

Fig. 8 is a top plan view of a one-way friction lock;

Fig. 9 is a vertical section taken on line 9—9 of Fig. 6;

Fig. 10 is a horizontal section taken on line 10—10 of Fig. 6; and

Fig. 11 is a horizontal section taken on line 11—11 of Fig. 6.

Referring to the several views of the drawings the stand comprises a tubular post or standard 15 provided at its lower end with a collapsible base such as a tripod 16 comprising three legs 17 which are bifurcated at the upper end to receive therebetween ends of straps 18, 19 and 20 which are encompassing the post 15 in the form of a collar

slidable on the post 15. The strap 18 has two parallel lugs 21 connected by a pivot pin 22 which extends through aligned apertures in ears 23 of a handle lever 24 formed at the upper end with an enlargement bearing on a pin 25 which extends through aligned apertures 15A and 18A respectively of the post 15 and strap 18 and is secured at the free end of a spring 26 secured at its other end to the inside of the post 15. To the lower end of the post 15 a collar 27 is secured and has articulated thereto three links 28 which are pivotally secured to intermediate portions of the legs 17.

It is evident that upon raising of the free end of the handle lever 24 the pin 25 is pressed inwardly thereby permitting the slideable strap collar to be raised until the legs are in collapsed condition, as indicated in dotted lines in Fig. 1.

The post 15 has a square cross section but may be round or rectangular if preferred, and may be covered at the top with a cap 29 which is apertured for the passage of an extension rod 30 bent at right angles at the upper end to provide an arm 31 having an indentation 32 (Fig. 5) for a purpose hereinafter described.

The screen 33 is adapted to be wound upon the elongated reel or roller 34 which is of the well known shade-roller type of construction, spring actuated, whereby its normal tendency is to keep the screen 33 wound thereon within a tubular casing 35 which is provided with a longitudinal slot 36 for the passage of the screen 33 and which slot is of less width than the diameter of a tubular member 37 to which the outer end of the screen is secured.

The tubular member 37 has a ring 38 secured thereto which when the screen is raised fits over the arm 31 and rests in the indentation 32.

The cap 29 has a slot 39 (Fig. 7) for the passage of an arm 40 formed integral with a rectangular member 41 whose opening 42 clears the rod 30 but is normally in slanting position to frictionally engage the rod with one edge as shown in Fig. 6 whereby the rod is secured against downward movement but permitted to be adjusted vertically and upwardly.

For downward movement the arm 40 is depressed to release rod 30 which drops under gravity. The rod 30 is formed with a horizontal bore 43 (Fig. 11) for the passage of a pin 44 headed at both ends, there being a spring 45 interposed between the rod and one head 46 of the pin 44 to cause the head to partially enter a hole 47 in the post to releasably lock the rod to the post. A pin 48 at right angles to the pin 44 traverses

the rod 30 and bears at both ends against the post to prevent rattling when the rod is moved vertically.

The screen casing 35 is adjustably secured to the post by a frame generally designated by 49 and constituting a handle as particularly shown in Fig. 6. The frame comprises a strap 50 which is bent to form a rectangle the horizontal portions 50^A having openings for the passage of the post and the rear vertical part 50^B being curved to present a convex surface to a hand.

The vertical strap ends at the forward end do not meet but are welded to a vertical circular disc 51. A horizontal pivot pin 52 extends through the apertured center of the disc 51 and has at the forward end a head 53 bearing against a disc 54 superposed on the disc 51 and rotatable thereon. The pin 52 has a pair of nuts 55 bearing on a cross-shaped centrally offset resilient washer 56 to hold the discs 51 and 54 under yieldable pressed face engagement with each other.

The disc 54 has a lug 57 which upon rotation is adapted to abut with a stop 58 on the disc 51 to limit the extent to which the disc 54 and the casing 35 may be rotated into horizontal position when the screen is extended in use.

To the disc 54 is secured by countersunk screws 59^A a strap 59 which partly encompasses and is welded or otherwise secured to the casing 35 to support the casing on the disc 54.

The casing is closed by end caps 61, one of which has an opening 62 into which extends a pin 63 projecting downwardly from the horizontally bent arm 31 of the extension rod 30 when the casing is in vertical position.

The handle frame 49, which carries the casing 35, is adjustably secured on the post 15 by a friction lock generally designated by 64.

The lock 64 comprises a lever 65 which has an opening 65^A to clear the post and is loosely secured to the upper horizontal portion 50^A by integral lugs 66 bent downwardly and under the strap portion 50^A and the free end of the lever 65 is held in raised or tilted position by a spring 67 interposed between the lever and the strap portion 50^A. In this tilted position, one edge 65^B of the lever opening 65^A frictionally engages the post and thus the casing 35 is adjustably frictionally secured to the post 15 against downward movement by gravity.

When not in use, the stand is in collapsed condition in which the flexible member 33 is rolled upon the roller 34 and the tubular member 37 is positioned to close the slot 36 in the casing 35 which is vertically aligned with the post 15 and locked to the arm 31 of the extension rod 30 through the pin 63 which extends into the opening 62 of one of the end caps 61 of the casing 35.

When in use, the casing 35 is swung into horizontal position in which it is held by the friction between the discs 51 and 54 imposed by the resilient washer 56. The tripod 16 supports the post 15 and screen 33 in vertical position when the screen 33 is unwound and supported on the arm 31 with the ring 38 securely positioned in the indentation 32 of the arm 31.

The extension rod 30 is vertically adjusted together with the screen until the desired height of screen is attained and thereafter the lock lever 64 is actuated to release the handle frame 49 and the casing 35 for adjustment to obtain desired area of the screen for the picture to be projected thereon.

Thus various vertical adjustments of the

screen may be attained not only as to height but also as to the area of the screen.

Also a predetermined area of screen may be vertically presented at various elevations by the adjustment of both the extension rod 30 and the casing supporting handle 49.

While the drawings show one embodiment of the invention various changes and alterations may be made without departing from the purview of the invention.

I, therefore, wish to include all modifications, variations and revisions which fairly fall within the scope of the invention as defined in the appended claims.

I claim:

1. In a stand, a support for a projection screen casing slidably mounted on a collapsible stand which includes a tubular post having a collapsible base, a vertically adjustable extension rod 20 slidably mounted in said post and normally releasably held against downward movement from its vertically adjusted position therein, and a casing mounted on said post and having a roller 25 therein, said roller having a screen windable thereon, said support for said casing comprising a substantially rectangular frame having vertically spaced horizontal portions provided with vertically aligned apertures through which said post extends, a vertical portion connecting said horizontal portions constituting a handle for carrying the stand when it is in collapsed position, a connection for said casing supported on said frame between said horizontal portions and opposing said handle portion including a pivot pin disposed transversely to said post, said casing being tilttable about said pin into parallel alignment with said post when the stand is in collapsed position, and frictional means for releasably securing said casing support in vertically adjusted position on said post.

2. A support for a projection screen casing as defined in claim 1, said connection comprising a plate secured to spaced vertically disposed portions of said frame, a plate secured to said casing disposed in face contact with said plate on said frame, said pivot pin extending through both of said plates and having a through end for a securing nut, and a resilient member mounted on said pin between said nut and said plate on said frame adapted to retain said plates in frictional engagement with one another.

3. A support for a projection screen casing as defined in claim 1, said connection comprising a plate secured to spaced vertically disposed portions of said frame, a plate secured to said casing disposed in face contact with said plate on said frame, said pivot pin extending through both of said plates and having a through end for a securing nut, and a resilient cross-shaped member mounted on said pin between said nut and said plate on said frame adapted to retain said plates in frictional engagement with one another, said cross-shaped resilient member having a central portion offset relatively to the outer ends of the arm portions of the cross form thereof and said central portion being in engagement with said nut and the ends of said arm portions being in engagement with said plate which is secured to said frame.

4. In a stand having a tubular post, a casing housing a screen, and a frame adjustable on said post and adapted to tiltably support said casing, a connection between said frame and said casing comprising a plate secured to said frame, a

second plate secured to said casing disposed in face contact with said first named plate and movable relatively to said first named plate, a bolt pivot pin extending through both of said plates and having a securing nut, and a resilient member mounted on said pin between said nut and said first named plate adapted to retain said plates in frictional engagement with one another.

5. In a stand as defined in claim 4, wherein said resilient member is cross shaped, said cross shaped resilient member having a central portion offset relatively to the outer ends of the arm portions of the cross form thereof and said central portion being in engagement with said nut and the ends of said arm portions being in engagement with said plate which is secured to said frame.

6. In a stand having a tubular post and a vertically adjustable extension rod slidably mounted in said post, frictional means for releasably locking said rod to said post, said means comprising a pin extending through said extension rod and being headed at both ends thereof, a

coil spring mounted about said pin between one of said pin heads and said rod, and an opening in the wall of said post adapted to receive therein a portion of the spring actuated head to thereby impose a frictional resistance to the movement of said extension rod outwardly of said post.

10 7. In a tripod stand, a tubular post having an aperture near its lower end, a collar shiftable on said post and having an aperture therein and a plurality of outstanding lugs, legs pivotally secured to said lugs, a second collar secured to the lower end of said post, links respectively articulated with said second collar and intermediate portions of said legs, a spring pressed pin in said post aperture adapted to extend through said aperture in said shiftable collar when said apertures are aligned, and a lever fulcrumed on said shiftable collar and adapted to force said pin from engagement with said aperture of said shiftable collar to permit adjustment of said shiftable collar relatively to said second collar.

HARRY E. ELLER.
